UNITED STATES PATENT OFFICE

146,821

DESIGN FOR A SCARF

Ivan Bartlett, Long Beach, Calif., assignor to Edgar C. Hyman Co., New York, N. Y., a firm composed of Edgar C. Hyman and Theresa M.
Hyman

Application December 3, 1946, Serial No. 135,230

Term of patent 3½ years

(Cl. D3—12)

To all whom it may concern:

Be it known that I, Ivan Bartlett, a citizen of the United States and a resident of Long Beach, in the county of Los Angeles and State of California, have invented a new, original, and ornamental Design for a Scarf, of which the following is a specification, reference being had to the accompanying drawing, forming a part thereof.

The figure is a plan view of a scarf showing my design.

I claim:

The ornamental design for a scarf, substantially as shown.

IVAN BARTLETT.
